(57) CLAIM

The ornamental design for a portable digital media player case, as shown and described.

DESCRIPTION

FIG. 1 is a front-elevational view of a portable digital media player case according to the invention;

FIG. 2 is a top-plan view of the case of the invention;

FIG. 3 is a bottom-plan view of the case according to the invention;

FIG. 4 is a left side-elevational view of the case of the invention, the right side being a mirror image thereof;

FIG. 5 is a rear-elevational view of the case of the invention;

FIG. 6 is a bottom plan view showing storage for ear bud headphones;

FIG. 7 is a rear elevational view showing the storage for the ear bud headphones; and,

FIG. 8 is a perspective view showing the storage for the earbud headphones.

The broken line showing of environment in the drawings is included for the purpose of illustrating only and forms no part of the claimed design.
